UNITED STATES PATENT OFFICE.

THEODORE A. MYERS, OF WHEELING, WEST VIRGINIA.

DESIGN FOR A TOY WHISTLE.

SPECIFICATION forming part of Design No. 21,408, dated March 15, 1892.

Application filed January 16, 1892. Serial No. 418,328. Term of patent 7 years.

To all whom it may concern:

Be it known that I, THEODORE A. MYERS, a citizen of the United States, and a resident of Wheeling, in the county of Ohio and State of West Virginia, have invented certain new and useful Improvements in Designs for Tin Whistles; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a side view of the invention, and Fig. 2 is a perspective view of the same.

This invention has relation to certain new and useful designs for toy whistles; and it consists in the novel form and configuration thereof, as herein shown and described.

The principal feature of the design consists in the form and configuration given the body portion of the whistle.

The letter A designates the body portion of the whistle, having the form and configuration of a bird's bill, the upper jaw portion *a* of which is extended rearwardly to form the mouth-piece portion B. The lower jaw portion *a'* also extends rearwardly beyond the point of connection between the two jaws, as shown at C. Back of the point of connection the jaw portions are shown as diverging from each other. Above the point of connection the jaw portion *a* is shown as having the form of a small portion of the front part of a bird's head.

Having described this invention, what I claim as new, and desire to secure by Letters Patent, is—

The design for a toy whistle, substantially as shown and described.

In testimony whereof I affix my signature in presence of two witnesses.

THEODORE A. MYERS.
